UNITED STATES PATENT OFFICE.

JAMES W. BOILEAU, OF CHICAGO, ILLINOIS.

CRUSHER.

1,191,494.

Specification of Letters Patent. Patented July 18, 1916.

Application filed February 8, 1913. Serial No. 747,061.

To all whom it may concern:

Be it known that I, JAMES W. BOILEAU, a citizen of the United States, residing at Chicago, in the county of Cook and State of Illinois, have invented certain new and useful Improvements in Crushers, of which the following is a specification.

My invention relates to that type of crushers in which two plates are mounted in opposition and at a downward inclination, one being stationary and the other reciprocable, the ore or other material being fed between the plates and crushed by a combined compressive and rubbing action.

15 The invention may be said to be in many respects an improvement upon that form of construction set forth in my former Patent No. 758,735, dated May 3, 1904, and has for its object the simplification of the machine 20 with an increase in strength and efficiency, reduction in the number of parts and the elimination of many wear points and also a modified movement of the reciprocating plate whereby greater crushing power is obtained and a finer range of adjustment by 25 which is attained a wider range of use and greater uniformity in the product.

In the accompanying drawings and in the following description predicated thereon is 30 set forth a preferred practical embodiment of the invention. As the constructional features are, however, capable of wide modification without departing from the essence of the invention it will be understood that the 35 drawing and description are to be construed in an illustrative sense and not as unnecessarily limiting the invention.

In the drawings: Figure 1 is a transverse vertical section on the line 1—1 of Fig. 2; 40 and Fig. 2 is a side elevation.

Having reference to the drawings in detail, the numeral 11 designates the machine bed plate having a central vertical opening 12 for the discharge of the crushed product 45 into a suitable receptacle. Supported upon the bed plate and strengthened by the ribs 13 is the substantially rectangular machine casing 14 open above. Although the machine may include one or any number of crushing units, I have illustrated a duplex machine in which two crushing units are mounted side by side to operate in alternating cycles.

As shown, the machine interior is divided 50 into two crushing chambers 15, 15 arranged one upon each side of the vertical axis of the

machine. The two units being in all respects identical the description of one will suffice for both. At one side of the machine and forming one wall of the crushing chamber 15 is disposed an inclined plate 16 formed of a rear supporting portion 17 and a front wear portion 18, the upper edge of this plate is provided with an hour glass slot 19 for the reception of the bolt 20 by means of which the plate is secured to the machine casing to provide for slight pivotal movement, the main body of the plate is disposed at an inclination to the vertical while the lower portion thereof is disposed in a substantially vertical position. Having a dovetailed engagement with the lower portion of the plate is an adjusting bar 21 extending the full width of the plate and between said bar and the inner wall of the casing itself at 22 75 is mounted an adjusting screw 23, by means of which the lower end of the plate 16 is adjusted in a horizontal direction upon the bolt 20 as a pivot. The rear face of the supporting plate portion 17 is provided with a 80 strengthening rib 24, while the front face of the wear plate 18 is provided with corrugations 25 in the form of teeth extending horizontally the full width of the plate and downwardly pointing. It will be observed 85 that these corrugations diminish gradually in size from the top toward the bottom and that the lower vertical face 26 of the plate 18 is smooth.

Centrally of the machine in the bearing 90 brackets 27 is journaled a rock shaft 28, each end of which is preferably squared as indicated in dotted lines at 29 to receive a walking beam 30, the free extremities of which beams are joined by means of the 95 cross rod 30^a and the connecting rod 31 to the crank 32 of a shaft 33 driven by a pulley 34 from any suitable source of power.

Upon the rock shaft 28 is keyed a pair of sleeves 35 each of which has upwardly projecting therefrom a pair of arms terminating in knuckles 36. The aligned knuckles 36 of the two sleeves 35 are connected by a rod 37 which rod serves as a pintle, its ends extending into knuckles 38 formed on the 105 upper ends of a swinging plate 39. This swinging plate is, like the plate 16, of duplex construction and comprises the rear supporting portion 40 and the front wear portion 41. The plate portions 40 and 41 110 are provided with a dove-tailed interengagement whereby the two portions may be

readily disassociated for the purpose of renewal or substitution of parts. The wear face of the plate 41 is convex, as shown, and presents in opposition to the plate 16 at similarly corrugated face, the corrugations 42 diminishing in size downwardly and the lower portion of the plate at 43 being smooth in opposition to the corresponding face of the plate 16. Extending the full width of the machine casing in line beneath the rock shaft 35 is an abutment bar 44 between which and the rear lower face of each of the plates 40 is loosely arranged an anti-friction roller 45.

15 It will be observed that upon the actuation of the walking beams 30 the shaft 35 is rocked so as to move the knuckles 36 about the axis of the shaft as a center through an arc confined substantially between a vertical plane passing through such axis and a plane disposed at an angle of approximately 45° to such vertical plane. By such rocking movement of the knuckles 36 the plates 39 are alternately reciprocated in a general vertical direction. However, it will be seen that the upper end of the plate moves in a curved line whereas the lower end of the plate moves in a vertical path along a substantially right line 30 upon its rolling support 45. The result is a combined compressive and rubbing action between the opposed faces of the plates 16 and 39, the compressive action being greatest in the upper portion of the machine 35 where the material is first introduced, while at the lower outlet portion between the smooth surfaces 26 and 43 the action becomes a purely rubbing one. By the adjustment of the lower ends of the plates toward and from each other the fineness of the product may be accurately controlled from coarse granular particles to an impalpable powder. As the rollers 45 are mounted for complete freedom of movement between the abutment bar 44 and the rear face of the reciprocating plates there is a pure rolling engagement therebetween and the friction at this point, which would otherwise be enormous, is practically eliminated.

50 I claim:

1. A crusher comprising facing plates arranged at an inclination to each other, one being fixed and the other movable, means to reciprocate one end of the movable plate in a curved line, and means serving as a rocking support for the other end of the plate whereby to maintain a substantially uniform distance between the fixed plate and the portion of the movable plate opposite the support.

2. A crusher comprising facing plates arranged at a downward inclination to each other, one of the plates being vertically reciprocable and the other substantially sta-

tionary, means to reciprocate the upper end of the first plate in a curved line, and means serving as a rocking support for the lower end of the stationary plate whereby to maintain a substantially uniform distance between the stationary plate and a portion of the reciprocable plate opposite the support. 70

3. A crusher comprising facing plates having their upper portions arranged at a substantial downward inclination to each other 75 and their lower portions more nearly parallel, one of the plates being vertically reciprocable and the other substantially stationary, means to reciprocate the upper end of the first plate in a curved line, means serving as 80 a rocking support for the other lower end of the second plate whereby to maintain a substantially uniform distance between the stationary plate and a portion of the reciprocable plate opposite the support, and 85 means to adjust the lower portion of the two plates toward and from each other.

4. A crusher comprising a freely suspended pivotally mounted plate having a wear face provided with horizontal corrugations 90, diminishing in size downwardly, a rear fulcrum support for the bottom of the plate whereby to maintain a substantially uniform distance between the fixed plate and a portion of the movable plate opposite the support, a stationary second plate having a similarly corrugated face disposed in opposition to the first plate, and means to reciprocate the top of the first plate in a vertically disposed curved path, substantially as described. 95 100

5. A crusher comprising a pivotally suspended plate having a wear face provided with horizontal corrugations diminishing in size downwardly, a rear fulcrum support for the bottom of the plate to confine the 105 same against lateral movement and to maintain a substantially uniform distance between the fixed plate and a portion of the movable plate opposite the support, a stationary second plate having a similarly corrugated face disposed in opposition to the first plate, means to reciprocate the top of the first plate in a vertically disposed curved path, and means to adjust the bottom of the second plate toward and from the bottom of the first plate, substantially as described. 110 115

6. A crusher comprising a rock shaft, rock arms carried thereby, a plate pivotally suspended from said arms and having a 120 wear face provided with horizontal corrugations diminishing in size downwardly, a rolling rear support for the bottom of the plate whereby to maintain a substantially uniform distance between the fixed plate 125 and a portion of the movable plate opposite the support, an inclined stationary second plate having a similarly corrugated face disposed in opposition to the first plate, and means to rock the shaft whereby to recipro- 130

cate the top of the first plate in a vertically disposed curved path, substantially as described.

7. A crusher comprising a rock shaft, upwardly disposed rock arms carried thereby, a plate pivotally suspended from said arms and having a wear face provided with horizontal corrugations in the form of downwardly pointing teeth diminishing in size 10 downwardly, a freely rolling rear support for the bottom of the plate whereby to maintain a substantially uniform distance between the fixed plate and a portion of the movable plate opposite the support, an inclined stationary second plate having a similarly corrugated face disposed in opposition to the first plate, and means to rock the shaft whereby to reciprocate the top of the first plate in a vertically disposed curved 15 path, substantially as described.

8. A crusher comprising a rock shaft, up-

wardly disposed rock arms carried thereby, a plate pivotally suspended from said arms and having a wear face provided with horizontal corrugations in the form of downwardly pointing teeth diminishing in size 25 downwardly, a freely rolling rear support for the bottom of the plate, an inclined stationary second plate having a similarly corrugated face disposed in opposition to the first plate, means to rock the shaft whereby to reciprocate the top of the first plate in a vertically disposed curved path and the bottom of the plate substantially in a right angle, and means to adjust the opposed 30 smooth faces at the bottoms of the plates toward and from each other, substantially as described.
